26 Cheap, Neutral Rugs, Apr. 21, 2020, found on May 2, 2020 at <https://www.architecturaldigest.com/gallery/26-cheap-neutral-rugs-that-actually-look-good> (Year: 2020).*

Primary Examiner — Karen S Acker*(74) Attorney, Agent, or Firm* — Andrew J. Mueller; Richard L. Alexander(57) CLAIM

The ornamental design for a rolled paper product, as shown and described.

DESCRIPTION

The sole FIGURE is a perspective view of a rolled paper product comprising our new design.

The broken lines and areas within them depict portions of the rolled paper product that form no part of the claimed design.

1 Claim, 1 Drawing Sheet(56)
